(57) **CLAIM**

The ornamental design for an automotive intercooler as shown and described.

DESCRIPTION

FIG. 1 is a perspective view of the automotive intercooler comprising the right-side tank and the left-side tank according to the present application;

FIG. 2 is a perspective view of the left-side tank of FIG. 1;

FIG. 3 is a bottom perspective view of FIG. 2;

FIG. 4 is a top view of FIG. 2;

FIG. 5 is a bottom view of FIG. 2;

FIG. 6 is a side view of FIG. 2;

FIG. 7 is a side view of FIG. 2;

FIG. 8 is a rear view of FIG. 2;

FIG. 9 is a front view of FIG. 2;

FIG. 10 is a perspective view of the right-side tank of FIG. 1;

FIG. 11 is a bottom perspective view of FIG. 10;

FIG. 12 is a top view of FIG. 10;

FIG. 13 is a bottom view of FIG. 10;

FIG. 14 is a side view of FIG. 10;

FIG. 15 is a side view of FIG. 10;

FIG. 16 is a rear view of FIG. 10; and,

FIG. 17 is a front view of FIG. 10.

The broken line showing is included for the purpose of illustrating unclaimed subject matter and forms no part of the claimed design.

The shade line showing is included for the purpose of illustrating contour and not surface ornamentation.
